UNITED STATES PATENT OFFICE.

FELIX W. LEINBACH, CLARENCE A. WOLLE, AND EDWARD H. BRUNNER,
OF BETHLEHEM, PENNSYLVANIA, ASSIGNEES TO CLARENCE A. WOLLE,
OF SAME PLACE.

PAPER-BAG MACHINE.

SPECIFICATION forming part of Letters Patent No. 242,661, dated June 7, 1881.
Application filed October 4, 1880. (No model.)

To all whom it may concern:

Be it known that we, FELIX W. LEINBACH, CLARENCE A. WOLLE, and EDWARD H. BRUNNER, all citizens of the United States, residing in Bethlehem, in the county of Northampton and State of Pennsylvania, have invented certain Improvements in the Manufacture of Paper-Bags and in Machinery therefor, of which the following is a specification.

10 Our invention relates to a modified form of the machine for which Letters Patent No. 218,036 were granted to our assignee on the 29th day of July, 1879, the main difference between the present machine and that patented being that, while in the patented machine the bags were made from plain tubes, in the new machine the bags are made from tubes having tucked-in sides.

15 The invention comprises certain features of construction and certain combinations of parts whereby a sheet of paper is first folded so as to form the tube with tucked-in sides, and this tube is then cut into lengths and formed into bags.

20 In the accompanying drawings, Figures 1 to 12, Sheet 1, are diagrams illustrating the successive operations in the manufacture of the bag; Fig. 13, Sheet 2, a side view of the complete machine; Fig. 14, a plan view of the same; Fig. 15, Sheet 3, a longitudinal section of the machine; Fig. 15₁, a detached perspective view of part of Fig. 15; Figs. 16, 17, and 18, transverse sections of Fig. 14, on the lines 1, 2, 3, 4, and 5, 6, respectively; and Figs. 19 to 30, Sheet 4, detached views of different parts of the machine, illustrating the working of said parts.

25 We will first describe the successive steps in the manufacture of the bag in connection with those parts only of the machine which act directly upon the web or tube of paper of which the bag is formed, reference being had to Sheet 1 of the drawings.

The paper, in the form of a web, X, of the proper width, is first drawn through a former comprising an upper plate, a, a lower plate, b, and an intervening block, d, shaped as described hereinafter, whereby the web of paper, as it is drawn through the former, has first a 30 V-shaped tuck formed thereon, as shown in

Fig. 1, this V-shaped tuck being gradually flattened until it assumes the condition shown in Fig. 2, and the flattened tuck being then folded inward, as in Fig. 3, prior to the bending of the opposite edges of the web of paper 55 inward beneath the plate b by means of fingers e, one edge of the web overlapping the other, as shown in Fig. 4. During this folding operation the web of paper and the inner edges of the tucks are pressed against the plate b by 60 a roller, e', carried by spring-arms e², so that the tension on the paper caused by folding the edges is prevented from disturbing the tucks. One or both edges of the web of paper have been previously pasted by any of the means 65 now employed in paper-bag machines—by the roller shown in Fig. 1, for instance—so that as the tube passes between the drawing-rolls the seam will be subjected to the necessary pressure and the tube with tucked-in sides completed. 70

It will be observed that the drawing-rolls and the pressure-roller e' are reduced in diameter at the ends, so that the edges of the tube are not subjected to pressure and are not flattened. The tube is fed forward over a table, A, and as it traverses a transverse pressing-blade, B, acts upon the tube at some distance from the end of the same, such pressure (owing to the fact that the edges of the tube are not flattened) causing the mouth of the tube to gape, so as to permit the free entrance of the distending-rod D, which moves in a direction contrary to that of the tube and blade B, as shown in Fig. 5. While these operations are being 80 performed a pair of hinged and folded plates, f, having inclined ends, are thrust into each of the side tucks of the tube, as shown in said Fig. 5, and as the movements of the plate B and rod D continue the plates f are unfolded, 85 as shown in Fig. 6, this operation serving to form the internal triangular flaps x, and to aid the distending-rod D in completing the primary fold of the bag-bottom, as in Fig. 7. The plates f are then withdrawn, the pressing-blade elevated, and the distending-rod retracted, so that the tube having the primary fold on the end of the same is free to pass on until said primary fold occupies a position directly over a yielding table, E, adapted to 90 95 100

an opening in the table A, as shown in Fig. 8, said opening being of the proper size for the desired bag-bottom. A plate, F, to the under side of which paste has been applied, 5 then descends, presses the primary fold of the tube against the plate E, and continuing to descend depresses said plate, thereby causing the unconfined flaps y y' of the primary fold to rise, as shown in Fig. 9, thus commencing the finishing-fold of the bottom. As the plate F descends it has a forward movement imparted to it, so as to insert the folded front edge of the tube beneath a pair of rollers, G G', as shown in Fig. 10, these rollers 10 serving to draw the tube forward while the plate F is retracted and caused to ascend. As the plate ascends the front edge of the same applies paste to the under side of the flap y, and vibrating fingers H H act on the flap y', 15 so as to fold the same beneath the plate F, as shown in Fig. 11, prior to the folding down of the flap y over said flap y', as shown in Fig. 12. The finishing-fold is now complete, and the proper pressure is applied to the same as 20 the end of the tube passes between the rollers G G'. The mechanism whereby the above-described operations are effected is illustrated in Sheets 2, 3, and 4.

J J are the opposite side frames of the machine, which are furnished with suitable bearings for the rollers G G', and for three pairs of shafts, i i', m m', and n n', the said shafts and the rollers being connected by suitable gearing, so as to revolve in the proper directions and 35 at the proper rate of speed. The side frames also have bearings for three transverse shafts, p, q, and s, the operations of which will be described hereinafter. The shafts i i', m m', and n n' carry, respectively, rollers I I', M M', and 40 N N', the rollers I I' and N N' being simple feed-rollers, but the rollers M M' being both feed and cutting rollers, the upper roller, M, carrying a transverse blade, and the lower roller, M', a transverse strip of rubber, cork, or like material, so that as the tube is fed forward by 45 the rollers it will be cut into proper lengths to form bag-blanks.

As before described, the former, whereby the tube with tucked-in sides is made from a single web of paper, comprises plates a and b and an intervening block, d. The plate a is gradually widened from the inner to the outer end, and the plate b and block d are partly straight and partly flared, the block d being somewhat 55 shorter than the plate b, and the plate a shorter than the block d, as shown in Figs. 13, 14, and 15. At and near each edge the plate a has on the under side a rib, a', which is V-shaped at the outer end of the plate, as shown by Fig. 60 16, but gradually merges into the thin vertical rib shown in Fig. 17. The opposite edges of the block d are inclined at the outer end of said block, as shown in Fig. 16, and undercut at the inner end of the block, as shown in Fig. 65 18, the two portions merging into each other, so that the edges of the block, at or about the center of the same, are substantially vertical,

as shown in Fig. 17. The plate b has on its opposite edges flanges b', said flanges flaring outwardly at the outer end of the plate, as in Fig. 16, and projecting inwardly, as shown in Fig. 18, at the opposite end, the outwardly-flaring position of each flange merging gradually into the inwardly-projecting portion, as shown in Fig. 17. The edges of the block 70 d and the flanges of the plate b thus form a recess corresponding in shape with the rib a' of the plate a, and, from the point at which the plate a is discontinued, the edges of the block d and the flanges of the plate b correspond with each other until said flanges and block are discontinued.

The pressing-plate B is carried by a pair of bars, c, one end of each of which is slotted and adapted to a guiding-pin on the adjacent side 85 frame, J, the opposite end being acted upon by a cam, m², on the shaft m', so that the elevation and depression of the plate at the proper intervals is effected. In order to effect the longitudinal reciprocation of the plate, each 90 bar c is connected, by a link, c', to the upper end of an arm, p', on the shaft p, and a rocking motion is imparted to the latter by a cam, m³, on the shaft m', said cam acting through the medium of an arm, m⁴, pivoted to a stud 95 on the frame, an arm, p², on the shaft p, and a connecting-rod, p³.

To the under side of the plate B, near each end of the same, is pivoted an arm, f', the outer end of which carries one of the pairs of hinged plates f before alluded to. The pivot-rods of the arms are bent at the lower ends, so as to form cranks f², which are acted upon by cam-plates f³, and the arms f' are acted upon by coiled springs f⁴, the tendency of which is to thrust said arms outward when the cranked ends of the pivot-rods are released from the control of the cams f³. Fingers t, having hooked ends, serve to fold and unfold the hinged plates f as the latter are traversed in the manner shown in Figs. 19 to 26, Sheet 4, these views representing the movements of one pair of plates, f, and the operating devices therefor. In Figs. 19 and 20 the plate B has been depressed and is just about to commence its 115 forward movement, the arm f' being extended and the plates f folded. As the plate B moves forward the cranked end f² of the pivot-rod of the arm f' is acted upon by the cam-plate f³, so as to cause the inward movement of the 120 end of the arm and of the folded plates f carried thereby, the forward movement bringing the plates f under the control of the finger t, by which they are unfolded, as shown in Figs. 21 and 22. Further forward movement of the 125 plate B effects the release of the cranked end of the pivot-rod of the arm f' from the control of the cam f³, and the spring f⁴ then causes the arm f' to swing outward, as shown in Figs. 23 and 24. The plate B is now elevated and 130 commences to move backward, when the hooked end of the finger t engages with the edge of the unfolded plate f and causes the refolding of the same, as shown in Figs. 25

and 26. There is no inward movement of the plates *f* during the rearward movement of the plate *B*, owing to the fact that the end of the pivot-rod of the arm *f'* is raised clear of the cam *f*³, and is not again brought into line with the same until the plate *B* reaches the limit of its rearward movement and is again depressed.

The distending-rod *D* is adapted to a groove in the feed-roll *N*, and the longitudinal reciprocation of said rod is effected by means of a bent arm, *v*, on the shaft *q*, a rocking motion being imparted to the latter from the shaft *p* through the medium of arms *v'* *v*² and a connecting-rod, *v*³. (See Figs. 13, 14, and 15.)

The plate *F* is secured to a bar, *F'*, which is hung to an arm, *w*, on a transverse shaft, *W*, adapted to bearings in brackets on the side frames, *J*, and having a rocking motion imparted to it from the shaft *n* through the medium of a crank, *n*², an arm, *w'*, and a connecting-rod, *w*². A transverse bar, *V*, carries a slotted block, *w*³, which embraces the bar *F'*, and serves as a guide and fulcrum for the same, as described herein after, a spring, *w*⁴, tending to keep the bar *F'* in contact with said fulcrum-block during a certain portion of the movement of said bar.

S is a paste-trough, in which is a roller, *S'*, the latter being rotated by means of a belt from a pulley on the shaft *n*.

The three positions of the plate *F* are illustrated in Figs. 27, 28, and 29, Sheet 4. On reference to Fig. 27 it will be observed that when the arm *w* is at the limit of its movement in one direction the plate *F* is adjacent to the roller *S'*. As the arm *w* commences to move in the direction of the arrow the plate *F* is brought into contact with the roller *S'* and receives paste therefrom, and as the movement of the arm continues said plate *F* is moved downward and away from the roller *S'*, this movement continuing until the bar *F'* is substantially vertical and bears against the fulcrum *w*³. (See Fig. 28.) Continued movement of the arm *w* in the direction of the arrow imparts a downward and slight inward movement to the plate *F* until the arm *w* reaches the horizontal position; but on continuing the movement beyond this the plate *F* will, owing to the bearing of the bar *F'* on the fulcrum *w*³, have an outward thrust as well as a vertical movement, as shown in Fig. 29, the object of this movement being to effect the tucking of the fold of the bag-bottom between the rollers *G G'*, as described in the first part of the specification.

The table *A* has guiding-strips *z*, whereby the bag-blank is properly directed to the plate *F* and table *E*, and the folding-arms *H* are inclined in respect to the surface of the table *A*, so as to insure a proper folding action on the flap *y'* of the bag-bottom. The said arms *H* are carried by shafts adapted to inclined bearings on the under side of the table *A*, and each of said shafts has an arm, *s*, to a slot in which is adapted the upper end of an

arm, *s*², on the shaft *s*, a rocking motion being imparted to the latter at the proper intervals by means of a crank-pin on the shaft *n'*, said crank-pin being adapted to a segmental slot in an arm, *s*³, secured to the shaft *s*. The segmental slot in the arm, in connection with the crank-pin, insures the necessary rapid vibration of the shaft *s* and the proper dwell between said vibrations, owing to the lost motion of the pin in the slot.

The machine is continuous in its operation, and can be driven at a very high rate of speed, both of which features are of importance in the manufacture of bags on a commercial scale, as it is essential that the bags shall be made rapidly and cheaply.

In carrying out our invention minor features of construction may be varied without departing from the general idea of the machine. For instance, the plate *b* and block *d* of the former may be made of one piece, suitably slotted and grooved, and the mode of hanging and operating the side-folding plates *f* may be modified, and in some cases the devices for forming the tube with tucked-in sides may be independent of the devices for making the bag from the tube, said tube being fed from one machine to another. The construction shown, however, is preferred as being more compact and economical.

It will be observed in Fig. 14 that the opposite ends of the plate *F* have **V**-shaped notches formed therein, so as to accommodate the triangular flaps *x*, formed in making the primary fold of the bottom.

We claim as our invention—

1. The mode herein described of making a tube with tucked-in sides, said mode consisting in pasting one or both edges of a longitudinally-moving sheet or web of paper, forming vertical tucks in said web at proper distance apart, gradually flattening and bending inward said tucks, and finally folding over and securing the edges of the web, all substantially as specified.

2. The combination, in a machine for making paper tubes or paper bags, of mechanism for longitudinally feeding a web or sheet of paper and pasting one or both edges of the same as it is so fed, a former constructed substantially as described, whereby vertical tucks are first formed in the web and then flattened and bent inward, and folding devices whereby the opposite edges of the web are caused to overlap each other and complete the tube, all substantially as specified.

3. The combination, in a paper-bag machine, of devices for feeding a tube, a longitudinally-moving rod and plate for distending and folding back the mouth of the tube, and laterally-moving plates for spreading and folding the tucked-in sides of the tube, whereby the primary fold of the bag-bottom is formed, all substantially as specified.

4. The combination, in a paper-bag machine, of devices for feeding a tube, a rod and plate for distending and longitudinally folding the mouth of the tube, side-folders for acting on

the tucked-in sides of the tube, a plate for transversely creasing the primary fold of the bottom, and folders for bending down and securing the flaps formed thereby, all substantially as specified.

5. The within-described former for tucking the web of paper, said former comprising the plate *a*, with rib *a'*, the plate *b*, with flange *b'*, and the intervening block *d*, with inclined and undercut edges, all substantially as set forth.

6. A former having slots merging gradually from a V shape at one end of the former into single contracted and inwardly-inclined slots at the other end of the former, as specified.

15. 7. The combination of tube-feeding and severing devices, the presser-plate, the distending-rod, two pairs of hinged plates, *f*, and means whereby said plates are folded and unfolded and carried laterally from and toward the tube, all substantially as specified.

8. The combination of a pressing-plate, *B*, arms *f'*, pivoted to said plate *B*, and hinged plates *f*, carried by said arms *f'*, as set forth.

9. The hinged folding plates *f*, each having a beveled inner end, whereby, when the plates are unfolded, said inner ends are adapted to the internal triangular flaps formed in the bag-bottom, all substantially as set forth.

10. The combination of the hinged plates *f* and their carriers with hooked rods *t*, for folding and unfolding said plates *f*, as set forth.

11. The combination of the pressing-plate *B*, and means for reciprocating and for elevating and depressing the same, the hinged plates *f*, the pivoted arms *f'*, carrying the same, the cranked rods *f*², the cam-plates *f*³, and the springs *f*⁴, as set forth.

12. The combination of the plate *B*, guided rods *c*, cams *m*², links *c'*, arms *p'*, rock-shaft *p*, and means for vibrating the latter, as set forth.

13. The combination of tube-feeding devices, a table, *A*, having an opening therein, rolls *G* *G'*, adjacent to said opening, a plate, *F*, and means whereby the plate is first moved verti-

cally to crease the tube, and then longitudinally to tuck the fold between the rolls *G* *G'*, as set forth.

14. The combination of a table having an opening therein, a paste trough and roller, a blade, *F*, and mechanism whereby a combined 50 vibrating movement over the paste-roller and a vertical reciprocating movement through the opening are imparted to the said blade, as described.

15. The combination of the table *A*, having 55 an opening therein, the yielding table *E*, the plate *F*, having a combined vertical and vibrating movement, the rollers *G* *G'*, the pivoted folding arms *H* *H'*, and means for operating said blade, rollers, and arms, as set forth. 60

16. The combination of the plate *F* and its bar *F'*, the shaft *W*, having an arm, *w*, to which said bar is hung, the fulcrum-block *w*³, the spring *w*⁴, and means for vibrating the shaft *W*, as set forth. 65

17. The combination of the pivoted folding arms *H*, the spindles of which have slotted arms *s'*, the arms *s*², adapted to the slots of the arms *s'*, the rock-shaft *s*, having an arm, *s*³, with segmental slot, and the shaft *n'*, having a 70 crank-pin, *n*², adapted to said segmental slot, as set forth.

18. The combination of the plate *b* of the tube-forming device, with the bending-fingers *e* beneath the plate, and the spring-pressure 75 roller *e'* above the same, whereby the tucks are confined and prevented from being drawn out by the action of the fingers *e* in forming the final folds of the tube, as specified.

In testimony whereof we have signed our 80 names to this specification in the presence of two subscribing witnesses.
